UNITED STATES PATENT OFFICE.

AUGUST BECKER, OF GÖTTINGEN, GERMANY, ASSIGNOR TO THE SPENCER LENS COMPANY, OF BUFFALO, NEW YORK.

MICROTOME.

SPECIFICATION forming part of Letters Patent No. 664,118, dated December 18, 1900.

Application filed August 25, 1899. Serial No. 728,520. (No model.)

To all whom it may concern:

Be it known that I, AUGUST BECKER, a subject of the German Emperor, residing at Göttingen, in the Kingdom of Prussia, German Empire, have invented new and useful Improvements in Microtomes, of which the following is a specification.

This invention relates to a microtome or slicing instrument designed for cutting very thin sections or slices from an object for microscopic examination.

The objects of this invention are to connect the knife-support with the operating hand-lever in such manner that the knife will not be displaced or disturbed by any deflection which may be caused in the operating-lever by the pressure exerted upon the same by the hand of the operator and to provide a simple and adjustable feed mechanism whereby the object is fed toward the path of the knife after each cutting operation.

In the accompanying drawings, consisting of two sheets, Figure 1 is a front elevation of my improved microtome. Fig. 2 is a top plan view thereof. Fig. 3 is a fragmentary horizontal section in line 3 3, Fig. 1. Fig. 4 is a vertical section in line 4 4, Fig. 1. Fig. 5 is a fragmentary vertical section in line 5 5, Fig. 1. Figs. 6 and 7 are fragmentary vertical sections at right angles to Figs. 4 and 5 and taken in lines 6 6 and 7 7, Fig. 2, respectively. Figs. 8 and 9 are horizontal sections in lines 8 8 and 9 9, Fig. 4, looking upward.

Like letters of reference refer to like parts in the several figures.

The main frame of the microtome consists, essentially, of an upright or standard A, of skeleton form, and a hollow base A', projecting forwardly from the lower end of the standard, as shown in Figs. 1 and 4. The frame may be secured in place in any suitable way, the means shown in the drawings being designed to secure the frame to the edge of a work bench or table and consisting of an upper clamping-jaw a, projecting rearwardly from the standard, and a vertical clamping-screw a', arranged in a lug a², projecting rearwardly from the standard.

B represents the horizontally-movable slicing-knife, which is secured near its ends by means of clamps c to a horizontal supporting-

bar C. This bar is pivotally connected at its ends with the upper part of the standard by a pair of horizontally-swinging rock-arms D D'. Each of the rock-arms is made comparatively wide in a direction parallel with its pivots, so that it is very rigid and not liable to become distorted. The rear end of each rock-arm is pivoted to the standard by upper and lower cone-screws d d', secured to the standard and engaging with conical sockets in the upper and lower sides of the arm. The front ends of the rock-arms are bifurcated and receive the ends of the horizontal knife-supporting bar C. The latter is provided at its ends with upright posts e e and is pivoted to the rock-arms by upper and lower cone-screws e' e², which are secured to the upper and lower members or branches of the bifurcated ends of the rock-arms and engage with sockets in the upper and lower ends of the posts, as shown in Figs. 1 and 6. The posts e e provide a wide bearing for the knife-supporting bar, which effectually prevents the same from being twisted or displaced.

The relative arrangement of the pivots connecting the rock-arms with the frame and the knife-supporting bar is such that a parallelogram is formed by these parts. The movement of the knife upon rocking the arms and knife back and forth is therefore similar to the curvilinear movement when drawing a knife by hand. The knife thus receives a movement which permits of utilizing nearly the whole length of the knife, thereby wearing the knife more uniformly and enabling larger slices to be cut from the object than has been possible heretofore. The knife is supported and guided solely by the rock-arms and supporting-bar, and these parts are sufficiently rigid to avoid any deflection of the knife out of its course in moving forward or backward, thereby producing sections or slices of uniform thickness.

The knife and its supports are rocked back and forth by a horizontally-swinging hand-lever F, which turns on the upper pivot-screw d of the right-hand rock-arm D'. The hand-lever bears with its upper side against the jam-nut e³ of this pivot-screw, and it is frictionally held in place by a spring-washer f surrounding said pivot-screw and interposed

between the under side of the hand-lever and the upper side of the frame. The hand-lever is provided near its pivot with a depending coupling-pin f' , which has a screw connection at its upper end with the hand-lever and which engages with its lower end in an opening f^2 in the upper side of the rock-arm D' , Fig. 5, in such manner that the coupling-pin is capable of some endwise play in this opening. The coupling-pin and the opening in the rock-arm D' are parallel with the pivot of the latter, so that upon turning the hand-lever horizontally the knife and connecting parts move only horizontally with the same. 15 If the hand-lever is deflected vertically by the operator while using the apparatus, the coupling-pin f' simply moves up and down in the opening of the rock-arm D' , but does not disturb the rock-arm and the knife connected therewith, thereby insuring a perfectly uniform cut of the slice from the object.

G, Figs. 1, 4, 5, and 9, represents the vertically-movable carriage or block which carries the device whereby the object is presented to the slicing-knife. This block is pivotally connected with the lower portion of the standard by two pairs of vertically-swinging rock-arms g , the pivots of which are so arranged that a parallelogram is formed by the frame, the supporting-block, and the arms connecting the same. By thus supporting the object to be sliced the same receives a parallelogrammatic movement toward the knife, and its top always remains in the same horizontal position, so that the slices cut from the object are always uniformly thick. The rock-arms of each pair are connected midway by a cross-bar g' and are pivoted at their rear ends to opposite sides of the standard by cone-screws g^2 and at their front ends to opposite sides of the supporting-block by cone-screws g^3 .

H represents a vertical feed-screw having a micrometer-thread whereby the supporting-block is raised and which engages with its upper screw-threaded portion in a threaded opening in the block, while its lower conical end rests freely on the flat head of a screw h , secured to the base. The feed-screw is held against accidental displacement by a frictional detent, consisting of a follower h' , arranged in an opening in the side of the supporting-block and bearing against the threaded part of the feed-screw, and a pressure-spring h^2 , secured to the supporting-block and bearing against the outer end of the follower.

The feed-screw is automatically turned for raising the supporting-block after each cut of the knife by the following mechanism:

I, Figs. 1, 4, and 8, represents a ratchet-wheel secured to the lower part of the feed-screw within the hollow base.

J is a pawl-arm turning loosely on the upper part of the hub of the ratchet-wheel and provided with a pawl j , which is yieldingly

held in engagement with the teeth of the ratchet-wheel by a spring j' .

K represents a vertical rock-shaft journaled in bearings in the frame and provided at its upper and lower ends with rock-arms k k' , respectively. The lower rock-arm k' extends forwardly and is provided with an upwardly-projecting pin k^2 , which engages with a radial slot k^3 in the free end of the pawl-arm. The upper rock-arm k extends forwardly, so as to stand in the path of the knife rock-arm D , and is provided with an anti-friction-roller k^4 . During the backward movement of the knife the knife rock-arm D engages with the roller of the upper feed rock-arm k and turns the same into the position shown in Fig. 3, which movement is transmitted by the rock-shaft, lower rock-arm, and pawl-arm to the ratchet-wheel and feed-screw for raising the supporting-block. During the forward movement of the knife the rock-shaft is turned in the opposite direction, so that the pawl takes up new teeth on the ratchet-wheel by means of a spring l , which surrounds the rock-shaft and is secured with one end to said shaft and with its other end to the main frame. The backward movement of the ratchet mechanism is limited by a stop m , which is arranged on the base and engaged by the lower feed rock-arm k' , as shown in Figs. 4 and 8. This stop is so located that the backward movement of the upper feed rock-arm k is arrested before the knife engages with the object during its forward movement, and after the knife has cleared the object during its backward movement the knife rock-arm D engages with the upper feed rock-arm k and turns the same for raising the block one space. By this means the feed of the object on the block takes place only during the last portion of the backward movement of the knife and at a time when the knife is wholly disengaged from the object, thereby preventing any injury to the apparatus and insuring accurate work.

As the supporting-block and the rock-arms connecting the same with the frame move upwardly the lower end of the feed-screw moves rearwardly slightly on the head of the screw h on account of the shortening of the distance between the feed-screw and the standard.

The extent of the oscillating movement of the feed-pawl is always the same, and in order to permit of varying the extent of each feeding movement of the feed-screw for varying the thickness of the slices which are cut from the object an adjusting device is provided, which is constructed as follows:

N represents an adjusting or cam disk mounted loosely on the lower end of the hub of the ratchet-wheel and provided with a cam-face n , which is adapted to be engaged by a pin or projection on the feed-pawl. During the last portion of the backward movement of the pawl its pin engages with the high or

salient part of the cam-disk, and the pawl is thereby disengaged from the ratchet-wheel during the remainder of its backward movement. During the first part of the subsequent forward movement of the pawl the latter is held out of engagement with the ratchet-wheel by the cam-disk until the pin of the pawl clears the high part of the cam-disk, and the pawl is then engaged with the ratchet-wheel by the spring j^1 , after which the pawl turns the ratchet-wheel and feed-screw until the end of its forward movement. By adjusting the cam-disk backward or forward the length of time during which the pawl is held out of engagement with the ratchet-wheel can be varied, and results in a variation in the extent of the effective or feeding movement of the pawl. The pawl-arm and cam-disk are held in place on the hub of the ratchet-wheel by two retaining-plates $o^1 o^2$, which are secured to opposite ends of the hub of the ratchet-wheel by screws o^3 . The cam-disk is adjusted by a horizontally-swinging adjusting-arm p , pivoted on the screw h and provided with a radial slot p^1 , which receives a depending pin p^2 on the cam-disk. This adjusting-arm projects forwardly through a slot p^3 in the base and is provided with a pointer p^4 , which traverses a graduated scale, whereby the extent of feed and the thickness of the slice which the knife cuts off from the object may be determined. This scale is preferably arranged at the front edge of a detachable plate q , which closes the top of the base.

When it is desired to lower the supporting-block and connecting parts, the feed-pawl is disengaged from the ratchet-wheel by the cam-disk, and the feed-screw can then be turned backwardly. For this purpose the side of the hollow base is provided with an opening r adjacent to the ratchet-wheel, which permits this wheel to be turned by means of a finger.

The object to be sliced by the knife is held in place by a freezing device, which is constructed as follows:

S represents an expansion-chamber which is secured upon the supporting-block G and which is preferably cylindrical in form and provided with a top or table S', upon which the object is placed. This expansion-chamber is provided in its side with a number of openings s and on its bottom with a depending stem s' , which is secured to the vertically-movable block by a clamping-screw s^2 .

T represents a guide-tube which extends diametrically across the lower part of the expansion-chamber and projects with its ends $t t'$ from opposite sides of the chamber, while its central portion within the chamber opens upwardly, as shown in Figs. 4 and 7.

t^2 represents an ether-nozzle which is inserted into the end t of the guide-tube and terminates with its inner end in the center of the chamber, while its outer end is connected by a flexible tube t^3 or otherwise with

a supply of ether. The inward movement of the nozzle into the chamber is limited by cooperating shoulders formed on the ether-nozzle and the guide-tube, and the supply of ether is regulated by a valve t^4 , arranged in the ether-nozzle. U is an air-nozzle which is introduced into the other end t' of the guide-tube until its external shoulder engages with a corresponding shoulder on the guide-tube. The inner end of the air-nozzle is provided with an upwardly-opening outlet, which is arranged below the outlet of the ether-nozzle, and its outer end is connected by a flexible tube u with an air-pump or other air-forcing device.

In order to guide the air and ether nozzles into the proper positions with reference to each other, each nozzle is provided with a V-shaped guide-lug u' on one side, which engages with a correspondingly-formed recess in the adjacent end of the guide-tube, as shown in Fig. 2.

Upon opening the ether-valve the ether issuing from the ether-nozzle is vaporized by the blast of air from the air-nozzle and thrown against the under side of the top or table S' of the expansion-chamber, whereby the temperature of the table is lowered to the freezing-point and the object to be sliced is frozen solid upon the table. By opening the ether-valve more or less the supply of ether may be varied as the process of freezing the object may require.

I claim as my invention—

1. The combination with the main frame and the object-support, of rock-arms pivoted to said frame, a knife-supporting bar carried by said rock-arms, a hand-lever for actuating the knife, and a yielding coupling which is interposed between said hand-lever and the knife-supporting bar and which is capable of yielding in a direction parallel to the pivotal axis of the hand-lever, whereby the latter can be deflected toward or from the knife-supporting bar without disturbing the position of the knife-supporting bar, substantially as set forth.

2. The combination with the main frame and the object-support, of rock-arms pivoted to said frame, a knife-supporting bar carried by said rock-arms, a hand-lever for actuating the knife, and a yielding coupling which is interposed between said hand-lever and the knife-supporting bar and which consists of a coupling-pin arranged parallel with the pivot of said lever and a socket which receives said pin and permits of the endwise play of the pin therein, substantially as set forth.

3. The combination with the main frame and the object-support, of vertically-swinging arms connecting said support with the main frame, a vertical feed-screw which engages said support and means for supporting the feed-screw in the main frame, permitting movement of the screw toward and from the pivots of said arms as the support is raised and lowered, substantially as set forth.

4. The combination with the main frame, the object-support arranged in front of the same, and a reciprocating knife-carrier, of vertically-swinging rock-arms extending from 5 said frame forwardly to said support, a vertical feed-screw engaging said support and capable of movement in the main frame toward and from the pivots of said arms, a ratchet-wheel secured to said screw, a pawl- 10 arm carrying a pawl which engages said wheel, a vertical rock-shaft which is journaled in the main frame and provided with an arm which engages said pawl-arm, a return-spring applied to said rock-shaft, and means where- 15 by said rock-shaft is actuated from the knife-carrier, substantially as set forth.

5. The combination with the main frame,

the knife and the object-support movable toward and from the knife, of a feed-screw engaging with said support and provided with 20 a ratchet-wheel, a pawl-arm provided with a pawl engaging with said wheel, an adjustable cam-disk mounted loosely on the ratchet-wheel and adapted to disengage the pawl from the ratchet-wheel, and an adjusting-arm pivoted on the frame and having a loose connection with said cam-disk, substantially as set forth. 25

Witness my hand this 28th day of July, 1899.

AUGUST BECKER.
